(57) **CLAIM**

The ornamental design for a display screen or portion thereof with graphical user interface, as shown and described.

DESCRIPTION

FIG. 1 is a front view of a display screen or portion thereof with graphical user interface;

FIG. 2 is a front view of a second embodiment thereof; and,

FIG. 3 is a front view of a third embodiment thereof. The broken lines showing the display screen form no part of the claimed design. The remaining broken lines showing portions of the graphical user interface and text form no part of the claimed design.

1 Claim, 3 Drawing Sheets(56)
